UNITED STATES PATENT OFFICE.

EMIL C. LOETSCHER, OF DUBUQUE, IOWA.

ELECTRIC SAD-IRON.

1,110,805.

Specification of Letters Patent. Patented Sept. 15, 1914.

Application filed August 31, 1911. Serial No. 647,119.

To all whom it may concern:

Be it known that I, EMIL C. LOETSCHER, a citizen of the United States, and resident of the city and county of Dubuque and State 5 of Iowa, have invented certain new and useful Improvements in Electric Sad-Irons, of which the following is a specification.

My invention relates to sad-irons with special reference to those heated by electricity, and has for its leading object to provide safe and efficient means whereby the heat will, not only be distributed all over the ironing surface, but largely increased along the edges and at the point end of the iron.

10 A further object is to provide means for constructing an electric heating unit which will distribute the heat in the manner aforesaid and will be simple in construction, will not readily burn out and can easily be re-placed.

In what it consists, its mode of construction and its manner of operation and installation, will be fully set out in the following specification when considered in connection with the drawings accompanying the same and forming a part hereof.

Figure 1 represents a longitudinal section through the sad-iron. Fig. 2 shows a plan view of the heating element as resting on the 25 base of the iron. Fig. 3 represents one of the insulating plates placed above and below the unit. Fig. 4 is an insulating plate placed between the overlapping parts of the heating element at the point. Fig. 5 shows a plan view of another mode of arranging the terminals, the mode of attachment and construction.

Referring to the drawings, 2 designates the base plate which is formed in the usual 40 shape and provided with an ironing or polishing bottom surface. Upon the base is placed an insulating plate 4 preferably of mica upon which rests the heating element or member 5, and over the member 5 is another insulating plate 4 upon which is fastened a cover plate 6 by screws 7 and 8 which fixedly hold the insulating plates 4 and heating member 5 upon the base. Over 45 all these parts and resting upon the base is a hood 10 which is secured to the cover plate 6 by the screws 12 and 14 which screws also serve to attach the handle 15 to the sad-iron.

The heating member 5 is made from a single straight strip of resistance alloy ribbon, stamped out to form slots or notches 55

from alternate sides whereby transverse ribbon-like portions are formed giving a zigzag conducting ribbon formation, whereby the current will travel in a zigzag path, and then, in order to make it conform substantially to the shape of the ironing surface of the sad-iron, and to bring the terminals 18 and 20 at the same end and further to increase the resistance and heat at the point 60 end 22 of the iron, the ribbon is folded upon itself substantially at the center and within the length of one of the transverse ribbon-like portions and into substantially V shape leaving it doubled at the end 24 of the sad-iron and the ends bent to conform to the curve of the edges of the base and leaving a space between the ends in the center of the base.

By over-lapping the member at the center 75 and by bringing the two ends or terminals near together the heating member will be curved edgewise causing the slots 16 to open on the outside edge and the slots on the inside to become narrower or close partially 80 together. There is, inside, between the overlapping parts, an insulating plate 26, shown in Fig. 4, which is provided with a notch 28 substantially of the width of the folded ribbon-like portion, said plate adapted to engage the bolt 8 and project between the slots at the center of the ribbon when it is folded. Care must be exercised in over-lapping the ribbon and in curving it lengthwise to prevent the same from buckling and to prevent 85 the edges of the slots from contacting with each other on the inner edge of the ribbon.

In order to keep the edges of the slots well separated and the conductor ribbon properly related to the polishing base, the terminals 18 and 20 must be spaced quite a distance apart, and for the purpose of bringing these terminals closer together whereby the introduction of the current is more conveniently and better introduced, the last 95 turn is folded upon itself and the terminals turned over bringing the two terminals closely together, as shown in Fig. 5.

In assembling the parts of my device whereby I accomplish the desired results I 105 place upon the base plate 2, a mica sheet 4 shown in Fig. 3. Upon this sheet 4 is laid the heating member 5, which is in a straight strip, and then fold it upon itself at the center and at the same time bring the terminals toward each other which will bend 110 edgewise the ribbon 5 till it will conform to

practically the same rounded shape as the ironing surface and when it has been brought to the position shown in Fig. 2 then the terminals are turned over bringing them to the position shown in Fig. 5.

Then the insulating plate 26 is inserted between the folded center of the member 5 with the slot 28 in engagement with the bolt 8. Over the member 5 is then laid another 10 insulating sheet the same as sheet 4 and upon this the cover 6. These parts are then securely bolted together by bolts 7 and 8. Over the sad-iron thus constructed are secured the hood 10 and the handle 15 by the 15 bolts or screws 12 and 14. The terminals 18 and 20 are attached to the terminal pins 13 which pass through the hood 10 and are insulated therefrom. A suitable flexible cord provides means for supplying the current 20 to the heating element.

It will be observed by this mode of constructing the heating member of a single straight metal ribbon with the slots on alternate sides and folding the middle upon 25 itself and by curving the ends edgewise to conform with the curve of the ironing surface the heat will be greatly increased at the point end and along the outer edges of the iron where it is most needed and where 30 the sad-iron cools first.

Having now described my invention what I claim and desire to secure by Letters Patent is:—

1. A resistance ribbon, provided with op-

positely extending transverse slots forming 35 oppositely extending transverse strips, the resistance ribbon being folded upon itself between its ends by bending one of the transverse strips thereof upon itself between its ends, for providing a substantially 40 triangular member including overlapping portions of substantial length, the longitudinal portions of the resistance ribbon which extend from the overlapping portions being slightly longitudinally bent, and an insulating plate adapted to be passed between the overlapping portions of the said strip and provided with a longitudinally extending slot to receive the bent portion of the said 45 strip.

2. A resistance ribbon provided with op- 50 positely extending transverse slots forming oppositely extending transverse strips, the resistance ribbon being folded upon itself between its ends by bending one of the 55 transverse strips thereof upon itself between its ends for providing a substantially triangular member including overlapping portions of substantial length, and an insulating plate arranged between the overlapping 60 portions near the bent portion of said strip.

In testimony whereof, I affix my signature in the presence of two witnesses.

EMIL C. LOETSCHER.
